(57) **CLAIM**

The ornamental design for a block M reflector, as shown and described.

DESCRIPTION

FIG. 1 is a perspective view of my design;
FIG. 2 is a front view thereof, a rear view being identical to the front view shown in FIG. 2; and,
FIG. 3 is a side view thereof, an opposite side view being identical to the side view shown in FIG. 3.
The dotted lines indicate environmental structure and form no portion of the design.
